D 19899

UNITED STATES PATENT OFFICE.

HARVEY BURDETT GOODWIN, OF ELMWOOD, CONNECTICUT.

DESIGN FOR A CUSPIDOR.

SPECIFICATION forming part of Design No. 19,899, dated June 10, 1890.

Application filed February 11, 1890. Serial No. 340,083. Term of patent 7 years.

To all whom it may concern:

Be it known that I, HARVEY BURDETT GOODWIN, a citizen of the United States, residing at Elmwood, in the town of West Hartford, county of Hartford, and State of Connecticut, have invented and produced a new and original Design for Cuspidors, of which the following is a specification.

The figure is a view of my newly-designed self-righting cuspidor.

The feature of my design consists in the outward curve A from a flat base to its largest

circumference, the inward curve B from this circumference to a circumference about equal in diameter to its base, and the outward and upward curve C to its top.

I claim—

The design for a cuspidor herein shown and described.

H. BURDETT GOODWIN.
